UNITED STATES PATENT OFFICE.

JAMES A. WATSON, OF WASHINGTON, DISTRICT OF COLUMBIA, ASSIGNEE TO BETHLEHEM STEEL COMPANY, OF SOUTH BETHLEHEM, PENNSYLVANIA, A CORPORATION OF PENNSYLVANIA.

PROOF OF FILE.

1,112,044.

Specification of Letters Patent. Patented Sept. 29, 1914.

Application filed December 16, 1910. Serial No. 597,712.

To all whom it may concern:

Be it known that I, JAMES A. WATSON, a citizen of the United States, and resident of Washington, in the District of Columbia, 5 have invented certain new and useful Improvements in Projectiles, of which the following is a specification.

Armor piercing projectiles are provided with points which are best adapted for 10 piercing armor plates and experiment has proved that the points best adapted for this purpose are not of such contour as to offer the minimum resistance to flight in the atmosphere. Stated in another way, the long 15 tapered conical point to which the atmosphere offers least resistance is too slender and weak to pierce armor without breaking. To secure maximum flight and maximum efficiency in penetration it has, therefore, 20 been proposed to construct the projectile with a somewhat obtuse point and to superpose upon it a hollow cap or wind shield of the contour to which the air offers the least resistance, the cap and projectile being, 25 of course, in axial alignment. The hollow caps are objectionable for the reason that if they are made of thin stamped or drawn metal they are likely to be injured or deformed before being fired, or to be bent out of 30 axial alignment with the projectile. If made of cast or heavy metal they are required to be machined internally as well as externally in order to make them perfectly 35 symmetrical. It is more or less difficult to attach thin hollow caps securely to the projectiles.

The object of the present invention is to overcome these difficulties and I accomplish this object by making the wind shield or 40 contour cap solid, and of a metal of low specific gravity, such as aluminum and some of its alloys. Solid caps of such material can be made of substantially the same weight as the hollow caps now in use, so 45 that the center of gravity of the projectile will not be disturbed by such a cap to any greater extent than by the hollow cap.

The invention will be described in connection with the accompanying drawing, in 50 which—

Figure 1 is a side view of a projectile provided with the usual soft nose or cap and with my improved contour cap, and Fig. 2

is a side elevation of the top of the projectile showing the caps in section on a larger scale than Fig. 1.

Referring to the drawing *a* indicates the projectile proper, *a'* the tip or nose of the projectile, *b* the usual soft steel cap which may be attached to the projectile in any suitable manner, and *c* the contour cap or wind shield. As shown the soft steel cap *b* is provided with a flange *b'* which interlocks with a groove *a'* on the projectile thus holding the cap securely upon the point of the projectile. The forward end of the cap *b* is provided with a threaded boss or projection *b''* and the base of the contour cap or wind shield *c* is provided with a threaded recess into which the boss is screwed. The contour cap, the soft steel cap, and the projectile are thus securely connected together in axial alignment. The outer surfaces *a'*, *b''*, *c'* of the base of the projectile point, the soft steel cap, and the contour cap, respectively, are 75 blended together to form a long tapered point of the general contour best adapted for flight through the atmosphere, that is, a point to which the atmosphere offers the least resistance, and which therefore enables 80 the projectile to travel farthest with a given initial velocity and angle of elevation.

The contour cap *c'* is made of aluminum, or of an alloy of aluminum sufficiently light to avoid material disturbance of the center 85 of gravity of the projectile by reason of the addition of the cap. Such a cap is cheap to construct and is not so liable to injury in handling as is a thin hollow cap. Moreover it is easily machined and it can readily be 90 made of uniform density, thus avoiding any possibility of its center of gravity being located outside of its longitudinal axis. The aluminum or alloy cap has also the further advantage of constituting a mass of lubricating material properly located to assist the projectile in penetrating a plate. It can be made sufficiently soft so that it will not interfere with the function of the soft steel cap at the moment of impact.

Having thus described my invention, what I claim as new and desire to secure by Letters Patent, is:

The combination with a pointed armor-piercing projectile and a soft metal cap secured to the projectile and surrounding and

supporting the point thereof, of a wind shield secured to the soft metal cap and tapered to reduce the resistance of the atmosphere to the flight of the projectile, the said wind shield being solid and composed of aluminum or other metal of lower specific gravity than the projectile and cap and sufficiently soft or fragile so that it will not

interfere with the functioning of the projectile at the moment of impact.

In testimony whereof I affix my signature in presence of two witnesses.

JAMES A. WATSON.
